HENRI JOSEPH BOUVIER, OF GRENOBLE, FRANCE.

DELIVERY-COMPENSATING AND RECOIL-DEADENING APPARATUS FOR WATER-MAINS.

1,357,838.

Specification of Letters Patent. Patented Nov. 2, 1920.

Application filed September 18, 1919. Serial No. 324,315.

To all whom it may concern:

Be it known that I, HENRI JOSEPH BOUVIER, a citizen of the Republic of France, and a resident of Grenoble, (Isère,) France, 5 have invented new and useful Improvements in Delivery-Compensating and Recoil-Deadening Apparatus for Water-Mains, of which the following is a specification.

Different types of delivery compensating 10 apparatus are known, in which the actuating means of the water distributing devices are operatively connected to a discharge valve, which opens during a certain period of time when the water distributing devices are being closed. The said delivery compensating 15 apparatus thus prevent, in some degree, recoils which may result from a more or less sudden closure of the water distributing devices; the apparatus, however, possess the 20 disadvantage of being useless when recoils are due to opening suddenly the valves, which may have for effect the formation of waves having periods of compression. On the other hand it is very difficult if not im- 25 possible to compensate for all positions and displacements of the valves; overpressures resulting from closing the distributors are therefore far from being completely avoided. 30 As, moreover, the delivery compensating valve is rigidly connected to the valves controlling the outlets of the water from the main, the closure of such valves necessarily entails the opening of the compensating valve.

35 On the other hand, recoil deadeners for water mains are known, such as described in my pending U. S. Patent application Serial Number 251,305, filed August 24, 1918, are intended to deaden recoil, whatever may 40 be the cause, by avoiding all overpressure in the mains.

Such apparatus is automatic in the sense 45 that the discharge valve is opened by an overpressure so soon as felt, whatever may be its cause; precisely by reason of this automatic action however, it may happen exceptionally that by accident the discharge valve cannot be moved or not in sufficient rapidity at the commencement of an over- 50 pressure.

The present invention has for its object an apparatus comprising the combination of the two apparatus, delivery compensating apparatus and recoil deadener, above set out, in order to obtain a unit, which possesses all the advantages of each separate apparatus and which works perfectly in all cases and from all points of view. Such an apparatus is shown, by way of example, diagrammatically, in the accompanying 55 drawing. B is a water main connected to a discharge aperture O, which is usually closed by a valve K³. K³ is a connecting rod jointed at g³ to a lever G¹ one end of which is connected by rigid members p, p¹ to a shaft P which controls the movement of the distributing valves of a turbine (or of apparatus utilizing the motive power of water under pressure); the connection is such that the end g⁴ rises when the distributing valves close, and falls when the valves open. The other end g² of the lever G¹ is connected by a rigid rod k to the rod K² of a piston K which works in a cylinder C. 75

The piston K is provided with a second rod K⁴ which is connected, directly as illustrated, or indirectly to a second piston K⁴ which works in a cylinder C⁴.

The annular face of the piston K⁴ is always in communication through a system of pipes D, D¹, D² with the main B or with an independent pipe containing liquid under pressure so that when a pressure of water is established at C¹ and C² and the 80 stresses exerted on both faces of the piston K are equal, the rod k is merely acted upon by the stress resulting from a pressure of water upon the annular face of the piston K⁴. The other face of the piston K⁴ is always at atmospheric pressure. 85

One or more spring valves N are provided in the piston K which open when the pressure at C² becomes greater than the pressure at C¹; if, however, the pressure at C¹ 90 becomes greater than that at C² the valves are pressed upon their seatings.

The spaces C¹ and C² are in constant communication with each other through a pipe L having a coned valve M whose position, 100

and therefore the free passage for liquid, is commencing from this movement, the piston K which has been constantly urged by the pressure exerted on the piston K^4 falls slowly, thus slowly closing the valve K^3 .

The lower space C^1 of the cylinder C is also in communication with the main B through a pipe D¹ which contains at some point a valve d; this valve opens when the pressure in the main becomes greater than that in the space C^1 and closes in the reverse case.

The upper portion C^2 of the cylinder C is in communication through a pipe J¹ and a valve H with an outlet pipe I.

The valve H is connected to a lever G by a connecting rod C and the lever G is jointed at g^2 to the rod k of the piston K.

The other end g of the lever is connected by a connecting rod b to a piston A which works in a cylinder E. Water under pressure passes from the main B and tube D and acts upon the upper face of the piston A which is also acted on by a constant force F (such as a counterweight or a spring having sufficient flexibility) equal and opposite to the stress exerted on the piston A when the main B is at a pressure equal to the static pressure.

There will be recognized from the foregoing:—

- 30 1. A delivery compensator formed of the discharge valve K^3 , the lever G^1 , the cylinder C and its piston K.
- 2. An automatic recoil deadener consisting; of an over pressure indicator formed of the cylinder E, the piston A and the counterweight F; of a differential servomotor formed of cylinders C, C⁴, pistons K, K⁴ and regulating valve M, of the valve H, and lastly of the discharge valve K^3 connected to the servo-motor which is capable of movement simultaneously with the piston K of the servo-motor.

The apparatus works as follows:—

First suppose that the distributors delivering water to the hydraulic apparatus which utilize the water power, are closed. The shaft P then turns in the direction of the arrow F².

The end g^4 of the lever G^1 is lifted and acts upon the piston K which however can only fall very slowly as the valve M leaves open a small passage only; on the other hand the valves N and d are on their seats. The discharge valve K^3 therefore lifts, allowing a certain quantity of water to flow away. The valve K^3 continues to lift until the closing movement of the distributors is ended.

During these two simultaneous movements two cases may arise:—

(a) The lifting of the valve K^3 is sufficient to prevent overpressure in the main B.

In this case the lifting movement of the valve K^3 will cease simultaneously with the closing movement of the distributors and

commencing from this movement, the piston K which has been constantly urged by the pressure exerted on the piston K^4 falls slowly, thus slowly closing the valve K^3 .

The valve N is regulated in such a manner that the speed of closing the valve K^3 can lead to no overpressure in the main B.

(b) It may happen that during the two simultaneous movements of the distributing valves and of the valve K^3 , the deliveries have not been compensated with sufficient exactness and that an overpressure is caused in the main B. In this case the overpressure acts upon the piston A which falls, thus rocking the lever G about its pivot g^2 , and in this case the valve H will fall, thus placing the annular space C^2 in communication with the outlet pipe I. The pressure at C^2 becomes less and the piston K will rise, thus opening the discharge valve K^3 at an increased speed and so preventing the production of any dangerous overpressure.

In this latter hypothesis, the delivery compensating apparatus and the recoil deadener act cumulatively and the two apparatus both coöperate, if necessary, to open the discharge valve K^3 and both act to prevent any dangerous overpressure in the main.

Suppose now that the distributors open more or less rapidly. The distributors are opened by rotating the shaft P in the direction of the arrow F² and has for effect to lower the end g^4 of the lever G^1 ; this lever therefore rocks about the pivot g^3 ; the end g^2 rises because the valves N open to allow the upward movement of the piston K. The lever G^1 thus rocks about its pivot g^3 and the discharge valve K^3 remains seated. The opening movement of the distributors will cause a certain lowering of pressure in the main B and when the opening movement ceases, a wave is produced in the main which may be translated into an overpressure which may be larger than in the first case because the distributors are opened more quickly. The automatic shock deadener now comes into operation. The piston A falls so soon as the overpressure makes itself felt, the valve H opens and causes a fall in pressure in the space C^2 ; the piston K is then moved upward and causes the discharge valve K^3 to lift. A flow of a certain quantity of water takes place through the discharge pipe O, which has for effect to prevent the overpressure becoming dangerous, and also for effect immediately to deaden the undulatory phenomenon which might be generated unless the discharge valve had operated.

It will be seen that in both cases the result is obtained of an automatic action of the deadener (which normal action prevents the formation of any dangerous overpressure in the main) combined with the effect

produced by the delivery compensating apparatus which is rigidly connected with the movement of the distributors for water under pressure; the two apparatus are thus 5 supplementary and their combination insures security of working in all cases.

Having now particularly described and ascertained the nature of my said invention and in what manner the same is to be performed, I declare that what I claim is:—

1. A delivery compensating and recoil deadening apparatus for water mains, comprising an indicator piston constantly subjected on one face to the pressure in the main, counter pressure means constantly acting on the other face of said piston for balancing to a certain limit the said pressure in the main, a servo-motor, means for operatively connecting the indicator piston 15 to a valve controlling the said servo-motor, means for operatively connecting the said control valve to the piston of the servo-motor, means for supplying with a fluid under pressure the cylinder of the servo- 20 motor, means for throttling the flow of liquid from one side of the said cylinder to the other side, means for operatively connecting the piston of the servo-motor to a discharge valve and to the actuating means 25 of the water distributing devices mounted 30 on the main.

2. A delivery compensating and recoil deadening apparatus for water mains, comprising an indicator piston constantly subjected on one face to the pressure in the main, counter pressure means constantly acting on the other face of said piston for balancing the static pressure exerted in the main, a servo-motor, means for operatively 35 connecting the indicator piston to a valve controlling the said servo-motor, means for operatively connecting the said control valve to the piston of the servo-motor, means for supplying with a fluid under 40 pressure the cylinder of the servo-motor, means for throttling the flow of liquid from one side of the said cylinder to the other side, means for operatively connecting the piston of the servo-motor to a discharge 45 valve and to the actuating means of the water distributing devices mounted on the main.

3. A delivery compensating and recoil deadening apparatus, comprising an indicator piston constantly subjected on one face to the pressure in the main,—counterpressure 55 means constantly acting on the other face of said piston for balancing the static pressure in the main,—a servo-motor with a differential piston, comprising a first piston, with equal annular faces, subjected on said 60 both faces to the same pressure of a fluid, associated with an auxiliary piston, of different diameter, subjected but on one face 65 to the pressure of a fluid,—a first cylinder

supplied on both sides with a fluid under pressure for the piston with equal annular surfaces,—and a separate cylinder supplied but on one side with the fluid under pressure for the auxiliary piston, means for 70 throttling the flow of fluid under pressure from one side to the other side of the first cylinder, means for operatively connecting the indicator piston to a valve controlling the servo-motor, means for operatively connecting the said control valve to the differential piston of the servo-motor, means for operatively connecting the said piston of the servo-motor to a discharge valve and to the actuating means of the water distributing 75 devices mounted on the main.

4. A delivery compensating and recoil deadening apparatus, comprising an indicator piston constantly subjected on one face to the pressure in the main,—counter- 80 pressure means constantly acting on the other face of said piston for balancing the static pressure in the main,—a servo-motor with a differential piston, comprising a first piston, with equal annular faces, subjected 85 on said both faces to the same pressure of a fluid, associated with an auxiliary piston, of different diameter, subjected but on one face to the pressure of a fluid,—a first cylinder supplied on both sides with a fluid 90 under pressure for the piston with equal annular surfaces,—and a separate cylinder under pressure for the piston with equal annular surfaces,—and a separate cylinder supplied but on one side with the fluid under pressure for the auxiliary piston, means for 95 throttling the flow of fluid under pressure from one side to the other side of the first cylinder, automatic valves mounted in the piston with equal annular surfaces for the purpose described, means for operatively connecting the indicator piston to a 100 valve controlling the servo-motor, means for operatively connecting the said control valve to the differential piston of the servo-motor, means for operatively connecting the said piston of the servo-motor to a discharge 105 valve and to the actuating means of the water distributing devices mounted on the main.

5. A delivery compensating and recoil deadening apparatus, comprising an indicator piston constantly subjected on one face to the pressure in the main,—counter- 110 pressure means constantly acting on the other face of said piston for balancing the static pressure in the main,—a servo-motor 115 with a differential piston, comprising a first piston, with equal annular faces, subjected on said both faces to the same pressure of a fluid, associated with an auxiliary piston, of different diameter, subjected but on one face to the pressure of a fluid,—a first cylinder supplied on both sides with a fluid 120 under pressure for the piston with equal annular surfaces,—and a separate cylinder supplied but on one side with the fluid 125

130

under pressure for the auxiliary piston, means for throttling the flow of fluid under pressure from one side to the other side of the first cylinder, automatic valves mounted 5 in the piston with equal annular surfaces for the purpose described, a lever operatively connecting the indicator piston, the control valve of the servo-motor and the differential piston of the latter, and another 10 lever operatively connecting the said differ-

ential piston of the servo-motor, the discharge valve and the actuating means of the water distributing devices.

In testimony whereof I have signed my name to this specification.
